UNITED STATES PATENT OFFICE.

ROBERT H. THOMPSON, OF BROOKLINE, MASSACHUSETTS.

TIME-STAMP.

1,393,410.

Specification of Letters Patent.

Patented Oct. 11, 1921.

Application filed July 25, 1917. Serial No. 182,783.

To all whom it may concern:

Be it known that I, ROBERT H. THOMPSON, a citizen of the United States, and a resident of Brookline, county of Suffolk, and State 5 of Massachusetts, have invented an Improvement in Time-Stamp, of which the following is a specification.

My invention relates to time stamps and has more specific references to stamps in 10 which the printing die is adapted to register its impression upon the top surface of the article to be printed.

Time stamps are usually constructed with a printing dial or die arranged on the top 15 of a base or anvil and driven by clock mechanism arranged within the base. The article to receive the impression is adapted to be placed in an inverted position over the dial and then struck a blow with a plunger ar- 20 ranged over the dial for this purpose.

This relation of the printing dial to the article to be printed has several bad features. The clock mechanism, being directly under the printing dial, is continually sub- 25 jected to the jars and vibrations resulting from the severe blows imparted to the instrument in its operation and therefore is soon rendered incapable of maintaining accurate time. The force of the blow neces- 30 sary to print the impression of the die must be transmitted through the article to be printed and if the article is at all bulky or heavy, the blow loses so much of its strength that the resulting impression is weak and 35 indefinite.

The necessity for inverting the articles to be printed, or printing it "blind," is an exceedingly bad feature of such a device. It is necessary in many cases, as in the printing 40 of time cards, for instance, that the imprint of the die be registered on a particular part of the paper or card and when the paper must be reversed to register this imprint, it is exceedingly difficult to locate the proper 45 portion of the paper with any degree of accuracy and this difficulty is so pronounced that, with special cards, the backs of the cards are provided with suitable markings to indicate the proper point of the card over 50 the die to register the imprint of the die on the proper part of the obverse side of the card.

The various objectionable features of a time stamp having a printing die arranged 55 on the base of the instrument and on which the article to be printed must be placed in

an inverted position on the die may be obviated in a time stamp in which the printing die is arranged over the anvil or base and in which the article to be printed is 60 placed on the anvil and under the printing die in an upright position. The clock mechanism for this arrangement of printing die and anvil is arranged in a separate casing on the base of the stamp and operably connected to the printing dial by suitable means. 65

An instrument as above described, has none of the objectionable features of the previously described type of time stamp. The dial actuating, on clock mechanism, being disposed in a separate case on the base 70 of the instrument entirely separate from the anvil and printing dial, is subjected to none of the shocks and jars inseparable from the operation of the device. The printing die, 75 being arranged above the anvil, permits the article to receive the impression of the die to be placed on the anvil in an obverse position and therefore the position of the impression on the paper or article can be ad- 80 judged with precision. The article, being placed directly on the anvil receives the impression directly on its top surface and therefore the imprint or blow necessary to register the impression is not transmitted 85 through the article to the printing die and therefore a comparatively weak blow on the printing head is sufficient to register a sharp, clear cut impression upon any article.

Time stamps have been heretofore con- 90 ceived with the printing dial movably ar- ranged above the anvil. The dial actuating mechanism, in such instruments, have been electro-magnets adapted to be periodically energized by clock mechanism entirely sepa- 95 rate from the instrument, and the periodical operation of the magnets, usually occurring once a minute, serves to actuate links and levers to advance the printing dial corre- 100 spondingly. The intermittent operation of the apparatus is objectionable and the construction of the mechanism, made necessary by the method of operation, is such that the continual jarring of the instrument, in its use, causes the printing dial to move inde- 105 pendently of its proper advancement due to the energization of the electro-magnets. It is also advantageous to provide the time stamp as a complete unit, that is, with clock- 110 mechanism, printing dial and anvil ar- ranged on one common base as with this unit construction the failure of any clock

to operate will incapacitate only its individual time stamp, and not a multitude of instruments as may occur if all the instruments in any office or factory are controlled 5 from one common master clock.

Consequently the object of my invention is to provide a time stamp with a printing dial arranged above an anvil, whereby the imprint of the dial may be placed on the 10 article in its obverse position; with clock mechanism arranged on the base of the instrument and entirely separate from the anvil or printing dial, whereby the mechanism will be subjected to no operating shocks; 15 and with means operably and positively connecting the clock mechanism with the printing dial whereby the dial is continuously moved to correspond with the hour and minute hands of the mechanism and 20 whereby the shocks of operation will not cause an improper operation of the dial.

Figure 1 represents a side elevation of a time stamp embodying my invention.

Fig. 2 is a plan view of Fig. 1.

Fig. 3 is a sectional view on line 3—3 of Fig. 2.

Fig. 4 is a plan view of the printing head.

Fig. 5 is a plan view of the printing head with the printing dial removed.

Fig. 6 is a sectional view of the anvil along line 6—6 of Fig. 1.

Fig. 7 is a partial sectional view showing method of pivoting the printing arm to the frame.

As here shown the time stamp includes the base 10 in which is integrally formed the anvil 11 and a casing 12 in which is adapted to be disposed the clock mechanism. The printing arm 13, which terminates in 40 the printing head 14, is pivoted in a slot in said casing 12 by screws 15 and the printing head carries a knob 16 which is adapted to be struck a blow to cause an impression to be recorded. The printing head 14 45 contains the printing die and other associated mechanism hereafter to be described.

Arm 13 is normally maintained in an elevated position against a suitable part of casing 12 which serves as a stop by means 50 of springs 17. The actuating, or clock, mechanism 18 is disposed as shown within casing 12 and is connected by means of suitable gearing 19 to the hands of a clock dial disposed in the top of the said casing and 55 more clearly shown in Fig. 2.

Casing 12 may have suitable openings therein for the insertion of a key to engage suitable shafts 20 and 21 of the clock mechanism by means of which said mechanism 60 may be wound and set. The printing die, located in the printing head 14 of arm 13, comprises a stationary die 22 on which are suitable clock numerals concentrically arranged thereon and said die has a recessed 65 center portion in which is revolvably dis-

posed an hour die 23 bearing the hour mark or arrow 24. Concentrically arranged within said hour dies is a minute die 25 bearing a minute hand or arrow 26. The printing portions of the stationary die and the 70

hour and minute dies are disposed in the same plane, whereby the impression of all dies may be registered with one operation.

The hour die is adapted to be driven from the shaft 25' of the minute die at the customary reduced rate by means of suitable reducing gearing 27. The stationary die 22 is arranged on, and the hour and minute dies 23 and 25 and the associated mechanism are supported by, a plate 28 secured 80

between the sides of the printing head 14. The shaft 25' of the minute die has arranged on its upper end a beveled gear 29 which is adapted to mesh with a similar gear 30 secured on the end of a short shaft 85

31 which is supported in suitable bearings 32 of plate 28. One member of a universal joint 33 is secured to the end of said shaft 31, the other member of which is secured to a short shaft 34. The other end of said 90

shaft is secured to one member of a second universal joint 35 the center of which is disposed approximately in line with the center of the printing arm 13 and the other member of said universal joint is secured to a 95

sleeve 36 which is slidably disposed on a shaft 37 of the clock mechanism. Sleeve 36 has a slot 38 in which is disposed a pin 39 secured to said shaft 37 by means of which

positive rotative connection is secured between said shaft 37 and the sleeve 36 which at the same time permits a relative sliding movement of said shaft and sleeve. The 100

sliding sleeve and universal joints just described constitute a flexible and positive connection between the clock mechanism disposed in the base of the instrument and the printing die disposed in the movable printing arm of the instrument above the anvil, whereby the continuous movement of the 105

clock shaft 37 is faithfully and accurately reproduced in the minute die of the stamp regardless of any movement of the printing arm.

An ink tape 40 is adapted to be disposed 115 over the face of the printing die and is wound upon two rolls 41 and 42 which are disposed in the printing head on opposite sides of the printing die. The shaft of these

rolls are so disposed in the side walls of 120 the printing head that they are securely maintained in position during the operation of the time stamp and yet are adapted for easy removal. Said shafts have knurled

thumb nuts number 43 and 44 secured on 125 the ends thereof by means of which the rolls may be rotated to bring a fresh portion of the ink tape carried thereon over the face of the printing die. Suitable die wheels 45 are,

or may be, disposed in the plate 28 at one 130

side of the printing die and a word wheel 46 is, or may be, disposed on the other side of said printing die and said word wheel has a thumb nut 47 secured to the end of its shaft whereby said wheel may be rotated to move any of the characters disposed thereon into printing relation with the ink tape.

A meridian wheel 48 bearing the letters A and P alternately disposed on its periphery is located in the plate 28 to one side of the printing die and a die bearing the letter M is disposed on the plate 28 on the other side of the printing die opposite to said meridian wheel. The combined imprint of the meridian wheel and the "M" die together indicate the meridian. The meridian wheel 48 is adapted to be operated once during every revolution of the hour die 20 and for this purpose the nut of the hour die has secured therein a pin 49 which is adapted to engage a pin 50 secured in a projection of a slide 51 whereby said slide may be moved to actuate said meridian wheel. Said slide 51 has formed therein a slot and disposed in its slot are two pins 52 and 53 which serve as guides whereby said slide 51 is constrained to move in a straight line. Said slide is normally maintained against one of said pins 52, by the tractable spring 54. A spring projection 55 is secured to one side of the slide 51 and is adapted, upon movement of said slide in one direction, to engage suitable teeth of projections 56 on the die wheel 48 to move said die wheel to change the impression to be printed but to inoperably engage the teeth thereon in a movement of the slide in the opposite direction. In operation, the rotation of the hour die moves the pin 49 carried thereby into engagement with the pin 50 secured in slide 51 and causes said slide to be moved to the right, see Fig. 5, against the tension of retractile spring 54 and to correspondingly move the spring 55 carried thereby away from engagement with the teeth on the meridian wheel 48. At the proper time, determined by the position of slide 51 with respect to the hour die and to the length of the pin 49, said pin 49 becomes disengaged from the pin 50 carried by said slide 51 and permits said slide to be drawn to its normal position by the retractile spring 54 and in its movement to said position the spring projection 55 secured thereon engages a tooth of the meridian wheel 48 and causes said wheel to be quickly moved to change its indication.

The anvil 11 of the time stamp is provided with a removable platen which, as here shown, comprises the metal base portion 57 suitably disposed in a groove in the anvil and which has a bent portion 58 by means of which said platen, may be removed by hand from the anvil. A resilient block

or pad 59 of rubber is secured to the top surface of said plate 57 and is adapted to receive the shock of impact when the instrument is operated. Said platen is made detachable from the base of the instrument 70 whereby the platen may be easily and cheaply renewed when it become worn.

I claim:

1. A self-contained time stamp having a base, an anvil carried thereby, clock mechanism on said base but substantially spaced from said anvil, a member attached to said base with capacity to be moved to and from said anvil to record an imprint, said member extending above said anvil, printing means 75 carried by said member above said anvil and arranged to be moved by said clock mechanism to make a record when an impression is made, and a flexible rotative shafting constituting a continuously operative connection 80 between said clock mechanism and said printing means to effect said movement from said clock mechanism.

2. A time stamp including a base, an anvil carried thereby, a clock mechanism arranged on said base remote from said anvil, an arm pivoted to said base and extended above said anvil, a printing die carried by said arm above said anvil adapted to be rotated by said clock mechanism, said arm 90 movable to and from said anvil to record an imprint of said printing die, a drive shaft connecting said printing die and a rotatable component of said clock mechanism for the rotation of said die by said clock mechanism, and a universal joint interposed in said shaft, whereby said shaft may be flexed during a movement of said arm for the imprint of said printing die and drive said printing die in such flexed condition. 100

3. A time stamp including, a base, an anvil thereon, a casing on said base remote from said anvil, clock mechanism disposed within the casing, a clock shaft rotatable by said mechanism, a printing arm pivoted to 110 the casing, a rotatable printing die carried by said printing arm above said anvil, a shaft journaled within said arm and operably connected with said printing die, a universal joint secured to said shaft, a sleeve 115 slidably arranged on said clock shaft to be rotated thereby, a universal joint secured to said sleeve, and a drive shaft connecting said two universal joints, said arrangement forming a flexible driving connection between said printing die and clock mechanism for the continuous rotation of said printing die in any position of said printing arm.

4. A self-contained time stamp having a 125 base, an anvil carried thereby, clock mechanism on said base but substantially spaced from said anvil, a member attached to said base with capacity to be moved to and from said anvil to record an imprint, said mem- 130

ber extending above said anvil, printing means carried by said member above said anvil and arranged to be moved by said clock mechanism to make a record when an impression is made, and a flexible driving connection between said clock mechanism and said printing means and structurally distinct from said clock mechanism and said printing means, and adapted to be continuously moved by and in accordance with said clock mechanism, thereby to move said printing means.

5. A self-contained time stamp having a base, an anvil carried thereby, clock mechanism on said base but substantially spaced from said anvil, an arm pivoted to said base and adapted to be swung to and from said anvil to record an imprint, said arm extending above said anvil, a printing die carried 10 by said arm above the anvil and arranged to be rotated by said clock mechanism to make a record when an impression is made, and a rotative shafting composed of a plurality of parts flexibly connected to each 15 other and adapted to be relatively moved when said arm is moved thereby to rotate said printing die in accordance with the rotative movement.

6. A self-contained time stamp having a 20 base, an anvil carried thereby, clock mechanism on said base but substantially spaced from said anvil, an arm pivoted to said base and adapted to be swung to and from said

anvil to record an imprint, said arm extending above said anvil, a printing die carried by said arm above said anvil and arranged to be rotated by said clock mechanism to make a record when an impression is made, and a wholly mechanical, continuous, rotative means flexibly connecting the 25 clock mechanism and the printing die to rotate the latter in accordance with the movement of the former.

7. A self-contained time stamp having a base, an anvil carried thereby, clock mechanism on said base but substantially spaced from said anvil, a member attached to said base with capacity to be moved to and from said anvil to record an imprint, said member extending above said anvil, printing means carried by said member above said anvil and arranged to be moved by said clock mechanism to make a record when an impression is made, and a rotative shafting 30 flexible both longitudinally and rotatively and constituting a continuously operative connection between said clock mechanism and said printing means to effect said movement from said clock mechanism.

In testimony whereof, I have signed my 35 name to this specification, in the presence of two subscribing witnesses.

ROBERT H. THOMPSON.
